UNITED STATES PATENT OFFICE.

JAMES J. HENNESSY, OF NEW YORK, N. Y.

LUBRICATOR.

Application filed July 27, 1922. Serial No. 578,020.

My invention relates to railroad rolling stock and comprises a lubricator adapted for use in M. C. B. journal boxes for forcing the lubricant from a reservoir below the journal up to the surface of the latter.

The objects of my invention are to provide a simple economical lubricator which may be inserted in the standard journal box without any additions or changes to the latter which will accommodate variations in the height of the journal due to differences in sizes or to wear on the journal brasses and which will permit the journal box to be jacked up when removal of the brasses or their wedges is desired.

In the accompanying drawings which illustrate a selected embodiment of my invention,

Figure 1 is a fragmentary longitudinal section through a journal and journal box with my lubricator applied thereto.

Figure 2 is a transverse section on line 2—2 of Figure 1.

Figure 3 is a section showing a slightly modified form of the lubricator delivery member.

In the drawings, the bottom of the journal box is indicated at 1 and the lower portion of the journal is indicated at 2. The journal is provided with a collar 3, the inner surface of which is engaged by a pump operating rod 4 slidably mounted in a lubricator member 5 and yieldingly held in its outer collar engaging position by a coil spring 6.

The lubricator body is preferably made in two parts, the upper member 5 being telescopingly mounted upon the lower member 7 which is adapted to be seated upon the bottom of the journal box. The outer periphery of member 5 slidably engages the inner periphery of member 7 and coil springs 8 yieldingly thrust these two members apart, the separating movement being limited by the engagement of pins 9 in the walls of member 7 with the ends of recesses 10 in member 5.

The device is narrow and is maintained in position in box 1 immediately under the axis of the journal by means of a perforated sheet metal plate 11 which fits around member 7 and engages the sides and ends of the journal box. This member may also be used to support waste packing if it is found desirable to use the same with my lubricator.

The lower member 7 of the lubricator comprises a pump cylinder 12 and an upwardly

extending barrel 13. A horizontal plunger 14 is positioned in cylinder 12 and may include the ball check shown or the flop valve construction described in my copending application Serial Number 578,068. A vertical pin 15 at the outer end of plunger 14 is slidably engaged by a sleeve 16 in rod 4.

A delivery element 17 is inserted in barrel 13 and extends upwardly therefrom to the face of the journal, having an extended bearing 18 against the latter. The upper portion of this element is supported upon a suitable seat on member 5 and a spring 19 compressed between a pin 20 in member 17 and a check valve 21 seated in the lower end of barrel 13 immediately over the pump cylinder cooperates with springs 8 to insure an operating position of member 17.

In Figure 3 I show a modified construction of the pump discharge elements in which the journal engaging element 22 is removable from the sleeve 23 which slides in member 7. This permits replacement of this part when worn or when a different sized journal is to be accommodated. Hence unnecessary duplication of parts in stocking the lubricator is eliminated.

It is apparent from an inspection of this construction that the upper member containing the contact rod and its return spring and seating the delivery element 17 is movable as a unit to and from the lower member containing the pump plunger and including a discharge chamber with a check valve. These two members although movable relative to each other, form an enclosure which protects the operating parts and the assembly of these members is such that the journal and journal box may be moved relative to each other as before indicated without removal of the lubricator and without damaging its mechanism.

I contemplate the usual modifications in the construction of my device as will be suggested by its commercial development and as are included in the scope of the appended claims.

I claim:

1. In a lubricator, a body member having a part adapted to be seated in a journal box and provided with a horizontally reciprocating pump plunger, said member having another part telescopingly assembled with said first-mentioned part and provided with horizontally reciprocating plunger operating means.

2. In a lubricator, a pump member adapted to be seated in the journal box and provided with a horizontal reciprocating plunger, a pump member assembled with said first-mentioned member to telescope vertically therewith and provided with a horizontal rod, the end of which is adapted to contact with the face of the collar of a journal in the box.
3. In a lubricator to be positioned in a journal box, a one-piece lower member adapted to rest upon the bottom of the box and comprising a pump cylinder and discharge barrel, an upper one-piece member having a sliding fit with said lower member and comprising an operating rod bearing and a delivery element support, a plunger in said cylinder, a journal engaging delivery element telescopingly mounted on said barrel, a journal engaging rod mounted in said bearing, a rod return spring seated in the inner end of said bearing, a telescoping connection between said rod and said plunger, and yielding means supporting said upper member on said lower member.
4. In a lubricator, a horizontal cylinder and a vertical outlet for said cylinder, a delivery element slidable in said outlet, a plunger reciprocating in said cylinder, a vertical pin on the end of said plunger, a horizontal operating rod located above said plunger, and a vertical sleeve for said pin on said rod said sleeve and pin forming a vertical adjustable connection between said plunger and rod.
5. In combination, a railway journal box, an axle journaled therein and provided with a collar, fluid lubricant in said box, telescoping lubricator elements positioned under the axis of said journal and provided with a pump extending below the surface of the lubricator and including a horizontal reciprocating plunger and a horizontal pump operating rod engaging the inner face of the collar on said journal, a telescoping connection between said rod and plunger, and cooperating vertical and horizontal yielding means respectively mounted on said elements for maintaining said rod in operating position.
6. In a journal lubricator, a body adapted to rest upon the bottom of a journal box and having vertical walls, an upper member engaging said walls and slidable vertically thereon, a horizontally reciprocating pump piston on said body, a horizontally reciprocating contact rod on said member, and a telescoping connection between said piston and rod.
7. In a journal lubricator, a body adapted to rest upon the body of the journal box, an upper member spring-supported on said body at spaced points, a horizontally extending pump and piston in the lower portion of said body and a horizontally movable operating rod in said upper member, and a connection between said piston and rod comprising interengaging members slidable vertically on each other but held against relative horizontal movement.
8. In a lubricator for railway journal boxes a body including a pump cylinder and a lubricant discharge passage, a member vertically telescoping with said body and having a lubricant delivery passage, an element on said member movable horizontally of said body to operate said pump, springs thrusting said body and member apart, and interengaging surfaces on said body and member for limiting the separating movements of the same.

In testimony whereof I hereunto affix my signature this 6th day of July, 1922.

JAMES J. HENNESSY.
